VAPOR LAMP.

1,414,466.

Specification of Letters Patent. Patented May 2, 1922.

Application filed July 21, 1919. Serial No. 312,186.

To all whom it may concern:

Be it known that we, CHESTER A. HOFF and JAY C. STEESE, citizens of the United States, and residents, respectively, of Akron, 5 in the county of Summit and State of Ohio, and Akron, in the county of Summit and State of Ohio, have invented a certain new and useful Improvement in Vapor Lamps, of which the following is a full, clear, and exact 10 description.

The present invention relates to vapor lamps wherein a fluid fuel is vaporized and mixed with air and burned.

One of the objects of the invention is to 15 provide a construction wherein there is employed a generator of relatively large capacity and arranged in series therewith a generator of smaller capacity, the generator of smaller capacity permitting the application 20 of a small amount of heat for the purpose of generating sufficient vapor to enable the ignition.

A further object is to provide a construction wherein the auxiliary vaporizer of small 25 capacity is directly carried by the vaporizer of larger capacity and is detachably secured thereto.

A further object of the invention is to provide a construction wherein both the main 30 generator and the auxiliary generator are removably carried by the lamp structure so that they may be assembled and disassembled with respect to the lamp as a unitary structure.

35 A further object of the invention is to provide a construction whereby the air which is mixed with the vaporized fuel is taken from a point away from the burners thereby insuring a supply of fresh air for the vaporizer and excluding the hot burnt air from the mantles.

A further object is to provide a construction 45 whereby the tube which conducts air to the bunsen portion of the lamp is movable so as to permit exposure of the vapor orifice which co-operates with the bunsen, thereby permitting cleaning of the aforesaid orifice.

Other objects of the invention will appear 50 more at large as the description proceeds.

55 Reference should be had to the accompanying drawings forming a part of this specification, wherein Fig. 1 is an elevation of a lamp embodying the invention, certain portions being shown in section; Fig. 2 is a front elevation of a portion of the lamp;

Fig. 3 is an elevation of an auxiliary generator used in connection with the lamp; Fig. 4 is a section on the line 4—4 of Fig. 2.

Referring to the drawings, 1 indicates a base which serves as a receptacle for containing fluid fuel, either gasoline, kerosene or similar fuel oil. Communicating with the base receptacle 1 is a tube 2 which serves as a generator tube, as will later be explained. Communication between the base receptacle 65 1 and the generator 2 is controlled by a suitable valve mechanism which is indicated at 3.

The generator 2 is more or less completely filled with a loose packing 4, of wire gauze or other suitable material which acts as a 70 strainer retaining the particles of carbon or heavier substances which are formed by the vaporizing of the fluid fuel.

One end of the tube 2 is threaded into what may be termed a yoke 5. This yoke provides 75 an open space 6. The upper part of the yoke 5 is threaded and receives a jam screw 7, which jam screw extends through an opening in a portion of the head 8. The portion which thus extends through the opening in 80 the head 8 is threaded as indicated at 7^a and is adapted to receive a ring nut 9 which when tightened securely holds the jam nut with respect to the head and by so much 85 definitely positions and locates the generator tube 2 with respect to the head 8. The ring nut has a ring portion 9^a which serves as a convenient finger grip for the purpose of turning the ring nut 9 and also serves as a support where it is desired to suspend or 90 hang the lamp.

The auxiliary generator tube is shown more particularly in Fig. 3 and comprises a tube 10 of comparatively small diameter. This tube is provided with a series of annular convolutions 11 and one end of the tube terminates in a fixture 12, which fixture has an extending portion 12^a and a flange like portion 12^b. In the fixture 12^a there is formed an orifice such as indicated at 12^c in 100 Fig. 1, this orifice being much smaller in diameter than the diameter of the pipe 10.

To the other end of the pipe 10 is secured a head 13, which head is hollow and has an opening 13^a. The lower portion of the head 13 is somewhat conical in shape, as indicated at 13^b.

As will be apparent from an inspection of Fig. 1, the head 13 of the auxiliary generator occupies the space 6 within the yoke 5 and 110

the slanting portion 13^b of the head 13 co-operates with the open end of the generator tube 2.

In order to hold the generator tube in position, the jam nut 7 engages with the head 13, thereby securely fixing and holding it with respect to the generator tube 2.

The fixture 12 which is carried by the tube 10 is adapted to cooperate with the tube 15 which is known as a Bunsen tube. This tube at its lower end is provided with one or more orifices which is indicated at 16. The lower end of the tube 15 is open and is adapted to receive the fixture 12. The tube 15 has an end member 17 provided with a central opening and into this opening the portion 12^a of the fixture 12 extends, the flange 12^b engaging with the outer side of the member 17.

The Bunsen tube 15 at its upper end is secured in a suitable opening in the head 8 which head is hollow, thereby providing a chamber within the head. Depending from the head are tubes 18 and 19. These tubes at their lower end are adapted to receive and support mantles 20.

It will be noted that the disposition of the tubes 18 and 19 is such that the mantles 20 lie upon both sides of the generator tube 2 so that this generator tube is heated when the vaporized fuel and air is burning at the mantles 20. It will further be noted that the auxiliary generator tube 10 is so positioned that it also extends between the mantles 20 so that the auxiliary generator tube is heated when the fluid fuel and air are burned at the mantles 20.

Of necessity the Bunsen tube 15 is located adjacent the mantles and unless some other way is provided, the air supplied to the Bunsen tube and passing through the orifices 16 would be the hot burnt air more or less directly emanating from the mantles 20. This is undesirable and in order to provide and insure comparatively cool and fresh air for the Bunsen tube, a tube 22 is provided which has an opening through which the Bunsen tube 15 extends. The fit of the tube 22 upon the Bunsen tube 15 is an easy fit so that the tube 22 may slide. Furthermore the tube 22 is of slightly greater diameter than the Bunsen tube 15 so that air passing through the tube 22 may circulate around the tube 15 and supply air to all the orifices in the Bunsen tube. The end of the tube 22 which is adjacent the Bunsen tube is closed by a plate 22^a.

When it is necessary or desirable to clean the orifice 12^c, this may be easily accomplished by sliding the tube 22 along the Bunsen tube 15, thereby exposing an orifice in the Bunsen tube and permitting the insertion of a small wire into the orifice 12^c.

In starting the lamp, a match is applied to the auxiliary generator 10, preferably at the coiled portion 11 thereof, then the

valve 3 is opened. The application of heat at this point is sufficient to cause the generation of a sufficient amount of vapor, within a few seconds time, so that the vapor may be ignited at the mantles 20. This is due to the fact that the pipe 10 is comparatively small in diameter so that a very direct application of heat to a small quantity of fluid fuel may be obtained. Usually the heat from a single match suffices for the purpose of starting the lamp.

When the vapor at the mantles 20 is ignited, heat incident to the vapor burning at the mantles is imparted to the generator tube 2, so that the principal vaporizing effect is obtained within the tube 2 but it will also be apparent that as the vaporized fuel passes through the smaller tube 10 it is further heated so that when the fluid fuel is delivered at the lower end of the Bunsen tube it is in thoroughly vaporized condition.

As before stated, the principal vaporized effect takes place in the tube 2 and in this tube there will collect substantially all the solid products of decomposition incident to vaporizing the fluid fuel. These solid substances will deposit upon the gauze or packing 4 and when necessary to remove them, the packing 4 may be withdrawn from the tube 2, and the tube thoroughly cleaned.

For the purpose of cleaning, it will be noted that by removing the ring nut 9, the generator tube 2 and the auxiliary generator 10 may be removed as a unit from the remaining portions of the lamp and by loosening the jam screw 7, the auxiliary generator may be removed from the main generator tube 2, thus permitting a quick and complete dissembling of the generator tubes for purposes already mentioned.

Having thus described our invention what we claim is:—

1. In a vapor lamp, a main generator tube and an auxiliary generator tube which communicates directly with the main generator tube, a Bunsen tube with which the auxiliary generator tube communicates, a pair of burner tubes with which the Bunsen tube communicates, the said main generator tube and the auxiliary generator tube lying between the said burner tubes.

2. In a vapor lamp comprising a chambered head, a burner tube depending from said head, a Bunsen tube depending from said chambered head, a main generator tube, an auxiliary generator tube carried by the main generator tube, said auxiliary generator tube communicating with one end of the Bunsen tube, means for securing the generator tube to the aforesaid head, the said generator tubes being removable as a unit with respect to said head and the parts associated therewith.

3. In a vapor lamp, a chambered head, a

- burner tube depending from said head, a Bunsen tube depending from said head, a main generator tube, an auxiliary generator tube, said auxiliary generator tube being arranged in series between the main generator tube and the Bunsen tube, means for securing one end of the auxiliary generator tube to the end of the main generator tube, the other end of the auxiliary generator tube having a sliding fit with the Bunsen tube, means securing the generator tube to the aforesaid head whereby the generator tubes may be removed as a unit from the head and the parts associated therewith.
4. In a vapor lamp, a chambered head, a burner tube depending from said head, a Bunsen tube depending from said head, a main generator tube, an auxiliary generator tube arranged in series between the main generator tube and the Bunsen tube, said auxiliary generator tube having a part which engages with the main generator tube, a jam screw for holding the said auxiliary generator tube to the main generator tube, said head being provided with a portion with which the jam screw cooperates and a nut cooperating with the jam screw for securing the same to the head, one end of said auxiliary generator tube communicating with the Bunsen tube.
5. In a vapor lamp, a chambered head, a plurality of burner tubes depending therefrom, a Bunsen tube depending from said head, a main generator tube, an auxiliary generator tube mounted upon the main generator tube, the said generator tubes lying between the aforesaid burner tubes and means for removably securing the generator tubes to the aforesaid head, the said generator tubes being arranged in series, one end of the auxiliary generator tube communicating with the Bunsen tube.

In testimony whereof, we hereunto affix our signatures.

CHESTER A. HOFF.
JAY C. STEESE.
